UNITED STATES PATENT OFFICE.

MARY NEAGLE, OF DILLON, MONTANA.

DESIGN FOR A MEMBER OF BROILERS OR TOASTERS.

SPECIFICATION forming part of Design No. 29,759, dated December 6, 1898.

Application filed November 9, 1898. Serial No. 695,986. Term of patent 7 years.

To all whom it may concern:

Be it known that I, MARY NEAGLE, a citizen of the United States, residing at Dillon, in the county of Beaver Head and State of Montana, have invented and produced a new and original Design for a Member of a Domestic Broiler or Toaster, of which the following is a specification.

This invention relates to a new and original design for a member of a domestic broiler and toaster; and it has for its object to provide a design of this character that shall be both useful and ornamental.

The leading feature of the design resides in a member of a broiler and toaster having a circular body provided with a marginal frame-ring of twisted wire, a smaller center ring lying within the plane of the marginal ring and concentric therewith, said smaller central ring having thereon closely-grouped annular coils and twisted body-strands arranged in the circular field between the two rings and converging on radial lines from the outer or marginal ring to the inner central ring.

A minor feature of the design resides in a body having extended from its marginal frame-ring at one side thereof a straight twisted handle-stem provided beyond its twisted portion with an oblong loop.

In the drawings Figure 1 is a plan view of a member of a domestic broiler and toaster embodying the herein-described design. Fig. 2 is a cross-sectional view on the line 2 2 of Fig. 1.

35 Referring to the accompanying drawings,

the numeral 1 designates the circular body of a broiler and toaster member, and this body is provided with an outer marginal frame-ring 2, formed of separate strands of wire twisted together. Arranged centrally within the outer 40 marginal frame-ring 2 and concentric therewith is an inner smaller central ring 3, having thereon closely-grouped annular coils 4 and having joined thereto the inner contiguous ends of the straight twisted body-strands 5. 45 The straight twisted body-strands 5 are grouped within the circular field between the inner and outer rings 2 and 3 and converge on radial lines from the outer ring to the inner ring, whereby the spaces between said 50 twisted strands flare as they approach the outer twisted marginal frame-ring 2. To complete the design, the circular body 1 is provided at one side with a straight handle-shank 6. This twisted handle-shank 6 is attached at one end to the marginal frame-ring 4 and beyond its twisted portion is provided with an oblong loop 7.

What is claimed is—

The design for a member of a domestic 60 broiler and toaster, herein shown and described.

In testimony that I claim the foregoing as my own I have hereto affixed my signature in the presence of two witnesses.

MARY NEAGLE.
